UNITED STATES PATENT OFFICE.

ALBERT J. D. OHM, OF NEW YORK, N. Y., ASSIGNOR TO INCANDESCENT SUPPLY COMPANY, A CORPORATION OF NEW YORK.

DESIGN FOR A RADIO PANEL.

Application filed September 24, 1925. Serial No. 14,887. Term of patent 3½ years.

To all whom it may concern:

Be it known that I, ALBERT J. D. OHM, a citizen of the United States, and residing at New York city, in the county of Queens and State of New York, have invented a new, original, and ornamental Design for Radio Panel, of which the following is a specification, reference being had to the accompanying drawings, forming part hereof.

The figure is a front view of the radio panel embodying my design.

I claim:

The ornamental design for a radio panel as shown.

ALBERT J. D. OHM.
